Esq.

(57) **CLAIM**

The ornamental design for a golf club speed training device,
as shown and described.

DESCRIPTION

FIG. 1 is a perspective in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines immediately adjacent the shaded areas, if any,
represent the bounds of the claimed design while all other
broken lines are directed to environment and are for illus-
trative purposes only; broken lines, if any, form no part of
the claimed design.

1 Claim, 7 Drawing Sheets
